UNITED STATES PATENT OFFICE.

CHARLES L. UIRY, OF NEWARK, NEW JERSEY, ASSIGNOR TO BIPPART & CO., OF SAME PLACE.

DESIGN FOR A LORGNETTE-CASE.

SPECIFICATION forming part of Design No. 31,672, dated October 17, 1899.

Application filed March 20, 1899. Serial No. 709,865. Term of patent 3½ years.

To all whom it may concern:

Be it known that I, CHARLES L. UIRY, a citizen of the United States, residing at Newark, county of Essex, State of New Jersey, have 5 invented a certain new and useful Design for a Lorgnette-Case, fully described and represented in the following specification and the accompanying drawing, forming a part of the same.

- 10 As shown in the drawing, my design comprises a lorgnette-case having a representation of the eyes and adjacent parts of peacock-feathers disposed upon the surface of the case.
- 15 As is well known, the eye of a peacock-feather has a conspicuous central ornament surrounded with wavy so-called "barbs," and each eye forms the terminal of the rachis or

stem of the peacock-feather to which the barbs are attached. In my design the stem and 20 barbs adjacent to each of the eyes fill the spaces between the eyes, so as to cover the surface of the lorgnette-case and constitute an all-over pattern.

Having described my design, what I claim, 25 and desire to secure by Letters Patent, is—

The design for a lorgnette-case, as shown and described.

In testimony whereof I have hereunto set my hand in the presence of two subscribing 30 witnesses.

CHARLES L. UIRY.

Witnesses:

ADRILL BIPPART,
THOMAS S. CRANE.
